MOTORCYCLE SADDLE BAG

Paul R. Jones, Norwalk, and Harold H. Larsen, Long Beach, Calif., assignors to Bates Industries, Inc., Long Beach, Calif., a corporation of California

Filed Oct. 31, 1966, Ser. No. 4,491

Term of patent 14 years

(Cl. D90—3)

FIG.1

FIG.5

FIG. 1 is a perspective view of a motorcycle saddle bag showing our new design;

FIG. 2 is a front end elevational view thereof;

FIG. 3 is a left side elevational view thereof; the right side elevational view being a mirror image;

FIG. 4 is a rear elevational view thereof; and

FIG. 5 is a bottom plan view thereof.

We claim:

The ornamental design for a motorcycle saddle bag, substantially as shown and described.
